UNITED STATES PATENT OFFICE.

PAUL KALISCH, OF ANTIGO, WISCONSIN, ASSIGNOR OF ONE-HALF TO JOHN KANZEL-BERGER, OF ANTIGO, WISCONSIN.

CAR STOP.

Application filed September 25, 1924. Serial No. 739,756.

To all whom it may concern:

Be it known that I, PAUL KALISCH, a citizen of Germany, residing at Antigo, in the county of Langlade and State of Wisconsin, have invented certain new and useful Improvements in Car Stops, of which the following is a specification.

This invention relates to a novel and improved car-stop to be used on railroads to stop cars at a certain predetermined point, especially during the car switching operations, and it is the principal object of the invention to provide a car-stop which is readily manipulated and of a simple and inexpensive construction, yet durable and efficient.

Another object of the invention is to provide a car-stop of this character which has an exchangeable wedge-shaped tongue adapted to make the stop a gradual one.

A further object of the invention is the provision of a car stop, the body of which is suitably grooved on its lower face to provide lateral depending flanges adapted to engage over the rail head and allowing the attachment of the wedge-shaped tongue.

It is also one of the objects of the invention to provide the car-stop with a handle allowing a convenient operation of the stop.

It will be clear that any number of these stops may be used in the daily operation and switching of cars, particularly freight cars which must be stopped at certain predetermined spots, for instance, in front of the platforms of ware-houses, switches, etc.

These and other objects of the invention and advantages thereof will become more fully known as the description thereof proceeds, and will then be specifically pointed out in the claim.

In the accompanying drawing, forming a material part of this disclosure:

Figure 1 is a side elevation of a freight car with a stop constructed according to the invention in place on one of the rails.

Figure 2 is a side view on an enlarged scale illustrating part of the car wheel with a stop constructed in accordance with the present invention in operative position.

Figure 3 is a section on line 3—3 of Figure 2.

The wheels 10 of a freight or other rail-

road car 11 of any customary construction and type run on rails 12 and adapted to engage the wedge-shaped tongue 13 of the car-stop gradually increasing in thickness towards its rear end.

The body 14 of the car-stop has its lower face grooved as indicated at 15 for the reception of the thicker end of the tongue 13 attached to the bottom of the groove by means of a plurality of fastening devices, for instance as shown, by threaded bolts 16 having heads in form of nuts 17 at their lower ends which are adapted to be embedded in a central longitudinal groove 18 provided in the lower face of the tongue 13. The side walls of the groove 15 in the body of the stop are shaped to form depending lateral flanges 19 and 20 engaging over the head 21 of a rail 12.

At its rear upper end the body 14 is equipped with a convenient and suitable handle 22 to allow a ready operation and handling of the stop while a stop shoe or tongue 23 is secured with its lower end in the stop body 14, while its upper end is shaped to follow the contour of a railroad car wheel as indicated at 24.

The operation of the device will be quite evident from the above description, the stop is placed on the rail at the place where a car pushed off by a switching engine, etc., is to stop, and it will be clear that the engagement between the car wheel and the gradually increasing wedge-shaped tongue will tend to slow down the movement of the car which will then be finally stopped by the engagement of its wheel flange with the projecting stop shoe 23.

Changes, such as fall within the scope of the appended claim, can be made in the general arrangement and in the construction of the minor details of the device without departure from the spirit of the invention.

Having thus described my invention, what I claim as new and desire to secure by Letters Patent, is:

Car stop comprising a substantially plane-shaped body having a lower groove extending longitudinally, flanges formed by the groove to laterally engage the rail head, a wedge-shaped tongue in said groove gradu-

ally increasing in thickness towards the rear and extending for a considerable distance beyond the front end of said body, said tongue having a groove in its lower rear face, a plurality of screw-bolts securing said tongue to said body, and nuts in the groove of said tongue on said bolts, a handle on the

upper rear face of said body, and a curved stop at the upper front end of said body having an upper end curved to conform to ¹⁰ the curvature of a car wheel.

In witness whereof I have affixed my signature.

PAUL KALISCH.
